LOCOMOTIVE SMOKE BOX FRONT

Filed Jan. 30, 1929

Fig. 3.

UNITED STATES PATENT OFFICE

HENRY K. HARWICK, OF DARBY, PENNSYLVANIA

LOCOMOTIVE SMOKE-BOX FRONT

Application filed January 30, 1929. Serial No. 336,200.

The object of my invention is to make the smoke-box front of a locomotive in a single casting, including the hinges, air pump brackets and pads, bell brackets, and reinforcing members. By my invention the front can be made comparatively light and accurate, and yet of great strength as it is preferably a steel casting.

In the accompanying drawings:

10 Fig. 1 is a front elevation of my improved smoke-box front;

Fig. 2 is a side view; and

Fig. 3 is a transverse sectional view on the line 3—3, Fig. 1.

15 The front 1 is circular in the present instance and has a series of perforations 2 near its periphery for the bolts which secure the front to the casing of the smoke-box.

20 Projecting from one side of the front are hinge brackets 3—3, on which the front can be swung to the open position when it is necessary to do extensive work in the smoke-box.

25 In the lower portion of the front is a man-hole opening 4. Surrounding this opening at the back is a reinforcing bead 5, and at one side of the opening are hinge-brackets 6 perforated for the pintles of the door (not shown) which is arranged to close the opening 4.

30 At the back of the fire-box front are two vertical reinforcing ribs 7—7, spaced apart and located one on each side of the door opening 4. A transverse rib 8 is located near the transverse centre of the front, and another transverse rib 9 extends across the upper portion of the front as shown. These ribs are 35 preferably tapered at each end as shown and all are located at the back of the fire-box front.

40 Projecting from the upper portion of the front are bell-brackets 10—10 shaped as shown and having trunnions 10_a for the bell.

45 At each side of the centre of the front are brackets 11—11 having pads 12 and ribs 13 for air pumps which are rigidly attached to the brackets at the pads. The brackets 11 are spaced from the front as shown.

This front may have pads for a head-light and signal fixture attachments, if desired.

50 In locomotives of the larger types it is

necessary to mount the air pumps at the front end of the smoke-box, as other acceptable locations would exceed the clearance lines.

While I have shown my improved front of a particular design, the shape and general design may be changed without departing from the essential features of the invention.

I claim:—

1. A cast metal smoke-box front for a locomotive, having integral reinforcing ribs at 60 the back; and integral air pump brackets at the front.

2. A cast metal smoke-box front for a locomotive, having integral hinges projecting at one side; integral air pump brackets on the 65 upper portion thereof; and a door opening in the lower portion.

3. A cast metal smoke-box front for a locomotive, having a door opening in the lower portion thereof; integral bell brackets projecting upwards; and air pump brackets projecting from the face front and arranged to support air pumps which are secured thereto.

HENRY K. HARWICK.
